FIG. 3

FIG. 4

FIG. 1 is a front perspective view of a wireless public address system receiver cabinet embodying my new design,

FIG. 2 is a side elevational view of the receiver cabinet;

FIG. 3 is a top plan view of the receiver cabinet; and FIG. 4 is a rear view of the receiver cabinet.

The elements shown in broken lines are included for illustrative purposes only.

I claim:

The ornamental design for a wireless public address system receiver cabinet, as shown.
